UNITED STATES PATENT OFFICE.

THOMAS CARROLL, OF DAYTON, OHIO, ASSIGNOR, BY MESME ASSIGNMENTS, TO THE NATIONAL CASH REGISTER COMPANY, OF DAYTON, OHIO, A CORPORATION OF MARYLAND.

TICKET PRINTING AND ISSUING MECHANISM.

Application filed October 27, 1919. Serial No. 333,523.

This invention relates to ticket issuing machines and has more particular relation to that class of ticket issuing machines adapted for use in issuing tickets for rail-
5 road and steamship lines or analogous uses.

The general object of the present invention is to provide an efficient and compact machine for use in railroad stations to issue tickets good only between the station at
10 which the machine is located and other established stations. It will readily be seen that the present embodiment is capable of other uses, such, for instance, as on steamship lines, ferry lines and other lines of local travel, in
15 fact in any place where tickets of different classes or prices are employed.

It is also one of the objects of this invention to control by the destination devices, or matrices, the actuation of the registering
20 and indicating mechanism of the type shown and described in United States Letters Patent No. 1,302,509 issued May 6, 1919, to Thomas Carroll.

In United States Letters Patent No. 1,
25 309,954 issued July 15, 1919, to Haakon A. Martin, there is shown and described a form of ticket issuing mechanism embodying detachable destination devices or matrices which control differential mechanism for
30 actuating totalizing means. In the present invention destination devices of a similar type are employed.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Of said drawings:

Fig. 1 is a front elevation of the machine embodying the present invention with
45 the cabinet removed.

Fig. 2 is a top plan view of the machine with part of the indicator mechanism omitted for the sake of clearness.

Fig. 3 is a detail of the cam for restoring tripped transfer devices to normal position.

Fig. 4 is a detail of the cam for aligning

the differentially and complementarily movable members.

Fig. 5 is a detail of the totalizer engaging cam.

Fig. 6 is a section taken on the line 6—6 (Fig. 1) looking in the direction of the arrows, but having a part of the indicator mechanism omitted.

Fig. 7 is a detail of one of the cams for actuating the differentially and complementarily movable members.

Fig. 8 is an enlarged detail of the front view of a one way ticket issued by the machine.

Fig. 9 is a section taken on the line 9—9 (Fig. 1) looking in the direction of the arrows, but having a part of the indicator mechanism omitted.

Fig. 10 is a detail of the indicator mechanism omitted in Figs. 6 and 9.

Fig. 11 is a detail of the indicator aligning cam.

Fig. 12 is a detail of the platen operating cam.

Fig. 13 is a detail of the ribbon feed and knife operating cam.

Fig. 14 is a detail perspective view of one of the destination devices.

Fig. 15 is a detail view showing the electroplate which is secured to the bottom of the destination device.

The machine in the drawings is constructed to add amounts of three denominational orders although its capacity may readily be increased without departing from the invention.

It is customary with a machine of this type to issue tickets of different classes. To accomplish this, separate destination devices are provided for each class.

The printing of the tickets is performed by destination devices which are in the form of detachable devices separately insertable into the machine, one of these devices of each class being provided for each station taken care of by the machine. When a ticket is to be issued, the destination device for printing on the ticket the desired class and the desired station of destination, is inserted into a chute. During the operation of the machine a ticket is fed over a platen

in a platen carrying frame and then severed from the ticket strip. The platen frame subsequently is elevated to carry the ticket into engagement with the destination device 5 to print therefrom.

While the destination device is in position to print on a ticket it is in cooperative relationship with the projections of differentially and complementarily movable members. The differential mechanism controlled by the destination device is employed to actuate a totalizer and also indicators. The destination devices are provided with amount determining means which in the 10 present instance are in the form of pins placed in different positions corresponding to the value of the tickets issued. Upon 15 operation of the machine the projections on the differentially and complementarily movable members move forward into contact with the pins.

Cooperating with the pins in the destination devices or matrices are three pairs of movable members, one member of each 20 pair carrying a total retaining device actuating rack. An invariably moved driving device carries the members forward until 25 projections on their forward ends engage the differentially arranged pins in the destination devices or matrices and then returns the members to zero. The arrangement of the pins is such that while the combined movement of the members of each 30 pair is always ten steps the movement of 35 the member carrying the actuating rack is in direct proportion to the value of the ticket issued. For example, if a ticket, whose 40 value is eight cents, is issued the rack carrying member will be caused to move eight steps and its companion member two steps during the subsequent operation of the machine while if the value of the ticket be two 45 cents the actuator member will have two steps of movement and its companion member eight steps of movement. Only nine of the ten steps of combined movement are controlled by the pins in adding operations, the 50 tenth step being controlled by totalizer elements to effect transfers. The total retaining device in the present embodiment is in the form of a totalizer. During the movement of the differentially and complementarily moved members the amount represented by the position of the pins in the destination 55 devices or matrices is entered on the totalizer. The transfer mechanism for the totalizer is so constructed that as a totalizer element passes from 9 to 0 a stop will be set to arrest the movement of the companion member for the actuating member of the 60 next higher order one step short of normal or zero position, thereby causing the higher actuating member to move one step farther than it otherwise would to turn the higher 65 order adding wheel an additional division.

Each amount entered on the totalizer is set up on indicators and displayed in the usual way. These indicators are of the short movement type, that is, they are moved directly from their last indicating positions to the positions indicating the new amount. The indicators are turned by 70 movements actuated through links having and pin connections with the rack bearing members. Movement of the 75 bearing members in one direction will rotate the indicators from lower to higher position. The indicators are turned in the opposite direction by pivoted levers 80 operatively connected to the companion members in such a way that while the members are all moving in the same direction the upper ends of the levers will be moved in the opposite direction. During this opposite movement the upper ends of the levers will contact with the pins on the links to turn the indicators from lower to higher positions, the levers and the slots in the actuating members cooperating at the end of the forward movement of the member to positively 85 limit the rotation of the indicators.

Driving mechanism.

The machine in the drawings is shown as constructed to be driven by means of 95 an operating crank 30 (Figs. 1 and 2) turning in a clockwise direction and fastened to the main driving shaft 31 journaled in the side frames 32 and carrying the main driving mechanism of the 100 machine. Any other form of driving means, however, may be provided. An auxiliary driving shaft 34 (Figs. 1 and 9) operates the ticket feeding mechanism and another driving shaft 35 operates the printing mechanism and also the knife mechanism.

Connecting the shafts 34 and 35 with the main driving shaft 31 is a train of gears (Figs. 2 and 9), one of which is a main 110 driving gear 33 fastened to the shaft 31 and meshing with an intermediate gear 37 pivoted upon a stud 41 in the frame member 42. Meshing with gear 37 and secured to the shaft 34 is a gear 43 (Fig. 2). Also 115 fastened to said shaft 34 and to the right of frame member 42 is a gear 44 meshing with a gear 45 (Fig. 9) secured to a shaft 46, said shaft being freely mounted in frames 42 and 47.

Freely mounted upon a stud 51 (Fig. 9) and in mesh with gear 45 is an intermediate gear 52 which also meshes with a gear 53 secured to a drive shaft 35 to operate the printing and knife mechanism hereinafter 125 described.

Destination devices.

A large number of destination devices 130 are used, as one device is provided for each

class of tickets issued to each of the stations taken care of by the machine. Each of the usual classes of tickets may be represented by a destination device, such for example as "Half fare", "Full fare", "Round trip", "One way", "Excursion", etc.

Each destination device 89 (Figs. 2 and 6) is provided with pins 65, 66, 67, 68, 69 and 70, arranged in pairs, there being one pair of pins for each denomination relatively arranged to correspond to the value of the tickets issued. These pins are the determining elements in accumulating various items representing different values of tickets issued, the mechanism for which is herein-after described.

The bottom side of each destination device 89 is provided with a suitable electro-plate 101 (Figs. 9 and 15) for printing a ticket 91 (Fig. 8). The data contained on these electroplates is shown by the small ticket 91, and includes the name 92 of the railroad or steamship line, the name of the place 93 at which the ticket is issued, the destination 94, the amount 95 paid for said ticket and a symbol 96 denoting the class of ticket, in this case it being a one way full fare ticket.

A plate 97 (Fig. 1) containing the name of a destination and the class of ticket, attached to the front end of each destination device serves as a guide in selecting a destination device and the proper end of said device for insertion in a chute 98. A further means for preventing the insertion of the destination device incorrectly are the guide grooves 99 (Figs. 1 and 14) in which the lugs 105 (Fig. 1) of the chute 98 slide.

The destination device 89 is held in its inserted position during the operation of the machine by a knife blade 100 (Figs. 1, 2 and 9) which at the beginning of the rotation of the operating crank 30 is elevated to a position partially closing the opening in the chute 98 in which position it remains until near the end of the rotation of the operating crank when it returns to its normal position permitting the removal of the destination device. The means for operating said knife blade 100 is hereinafter described.

To remove the destination device 89 from the chute 98 the fingers are placed upon said device 89 through the opening in the top of the chute 98 (Fig. 2) and by a slight motion of the fingers said destination device will slide through the opening in the front of the chute 98 a sufficient distance to enable it to be easily withdrawn.

Differential mechanism.

As previously stated, the differential mechanism comprises a plurality of pairs of differentially and complementarily movable members. Each of these pairs comprises a rack bar member 106 (Figs. 1, 2, 6 and 9)

and a companion member 107. The members of each pair are close together and have slots 108 and 109 surrounding respectively a rock shaft 90 and the driving shaft 31. Extending through the slots 109 is a rod 74 supported at each end in a pitman 71 (Figs. 2, 6 and 7). Both of these pitmans are slotted at their rear ends to engage studs 75 fastened to extensions 80 (Figs. 2 and 6) on the rear machine frame 81 and at their forward ends are slotted to engage the driving shaft 31. Mounted on the rod 74 is a pinion 110 (Fig. 9) for each pair of members. These pinions mesh with racks 111 and 112 fastened respectively to the actuating members 106 and companion members 107. Each of the pitmans 71 carries a roll 72 (Figs. 2, 6 and 7) which projects into a cam slot 113 in disk 57. The disks 57 are fixed on shaft 31 and rotate in a clockwise direction. The cam grooves 113 are so shaped that at a rotation of the shaft 31 the pitmans 71 will be moved forward and then back an invariable extent. This movement of the pitmans 71, because of the engagement of the pinions 110 with the racks of the complementarily movable members will carry the members forward until they are arrested by projections 114 and 115 (Fig. 6) on their forward ends engaging pins 65 and 66, 67 and 68, or 69 and 70 differentially arranged on the destination device.

Fig. 2 shows a destination device properly placed in the machine and having the pins positioned so as to record an item of \$5.59, which item is shown on the sample ticket (Fig. 8). On referring to the first pair of complementarily movable members on the right (Fig. 2) when the rod 74 and pinions 110 (Fig. 9) are drawn forward the complementarily movable member 107 will move forward one step into engagement with the pin 65 which will retain member 107 while its companion member 106 will move forward nine steps into engagement with the pin 66. During the operation of the middle or second pair of complementarily movable members the member 107 will move forward five steps into engagement with pin 67 while its companion member 106 will move forward five steps into engagement with pin 68. In the operation of the third pair of complementarily movable members the member 107 will travel forward ten steps to engage with the pin 69 and therefore its companion member 106 will not move forward but will remain in its normal or home position being held there by engagement with pin 70. Movement of one of the members after the other has been stopped is, of course, due to the fact that during the remainder of the forward movement of the rod 74, the pinion 110 will rotate about the rod and will also roll along the rack attached to the member held stationary.

The construction is such that when the rod 74 reaches the limit of its forward movement the elements 106 and 107 will both be held firmly in engagement with the pins in the destination devices. In zero operations, it will be recalled, the elements 106 are held stationary by the pin on the left in each pair, as is shown by pin 70 (Fig. 2), while the elements 107 are given the full ten steps of movement. When the elements 106 and 107 are returned to their rearward positions they will both be arrested positively, as herein-after explained. The construction is such that movement of members 106 is always positively controlled. This is a valuable feature of the construction as the members 106 carry actuating racks 116 for operating the totalizers and the positive control of the members prevents any chance of wrong addition by making it impossible for the actuating members to be given a wrong extent of movement.

Totalizing device.

A full detail description of the totalizer is given in the Carroll patent previously referred to, and it will be only briefly referred to herein.

The totalizing device is carried in a rock frame 117 (Figs. 2, 6 and 9). This frame comprises a yoke having mounted therein two hubs 118 pinned to a shaft 119 journaled in the side frames 32. Said frame 117 has on its left side an arm 120 extending downward and to the rear, and mounted near the end is a cam roll 121 which engages with a cam slot 122 formed in the cam 59 fixed to the driving shaft 31. (Figs. 2 and 5.) The cam slot 122 is so shaped that at each rotation of the driving shaft the totalizer frame 117 will be rocked, first counter clockwise (Figs. 6 and 9) and then clockwise. The first of these movements of the frame 117 engages the totalizer with the racks 116 on members 106 and occurs after the actuating members 106 have been differentially positioned under the control of the stops 65, 66, 67, 68, 69 and 70 (Figs. 2 and 6) so that when the members 106 are returned to their rearward positions the racks 116 will operate the totalizer wheels 123.

The totalizer adding wheels 123 are rotatably mounted on a shaft 124 (Figs. 1, 2, 6 and 9) journaled in the frame 117. Rigid with each of the three lower order adding wheels is a pinion 125 adapted to engage the teeth 116 of the member 106. The other three wheels of higher order receive the overflow from the first three wheels and are affected directly by movement of the next lower order adding elements.

The mechanism for effecting transfers from lower to higher orders will next be briefly described. The units and tens of cents adding elements of the totalizer control re-

spectively the actuating members 106 of the tens of cents and units of dollars orders to cause the actuating members to have an added step of movement when transfers are to be turned in. This transfer mechanism is substantially the same as that disclosed in the U. S. Patent to Carroll, 1,265,301, granted May 7, 1918, to which reference may be had for a more complete disclosure. It comprises a hub 220 on each lower totalizer wheel provided with a recess and tooth 221 for cooperation with a locking plate 222 and a toothed plate 223 secured together and cooperating with pins 224 and 225 on the plates 106 and 107 in the usual manner. The transfers to the fourth, fifth and sixth adding elements are effected directly by movement of the next lower order adding elements.

The transfer elements are restored to their normal position after a transfer is made as the shaft 90 (Fig. 6) is rocked in a clockwise direction by a cam 54 (Figs. 1, 2 and 3). Engaging with said cam 54 is a cam roll 63 carried on a stud mounted in a pitman 62. The forward end of pitman 62 is pivoted on a stud 73 mounted in an arm 64 (Figs. 1, 2 and 6). The arm 64 is pinned to the shaft 90 and will rock said shaft at the proper time during the rotation of the cam 54.

The actuating members 106 are aligned at the end of their rearward movement by an aligning frame 79 pivoted on the rod 78 journaled in the tie bar 81. The cross member of the aligning frame 79 is beveled at its upper edge to engage with notches 82 in the lower edges of the actuating members 106. As shown there are two notches on each of these members, the rear notch being in position to co-operate with the aligning frame 79 when no transfers have been turned in, the other or forward notch being in position to be engaged when the actuating member 106 has been given an additional step of movement rearward to turn in a transfer. This aligning frame 79 is operated by an arm 76 (Figs. 1, 2, 4 and 6) secured thereto and carrying in its upper end a cam roll 77 which engages with an open cam 56. This cam is so shaped as to rock the aligning frame 76 into engagement with the notches 82 in the actuating members 106 at the proper time for alignment. At the beginning of each rotation of the cam the roller 77 will be freed, thereby allowing the arm 76 and aligning frame to drop far enough to disengage the aligning frame 79 from the notches 82. As the cam 56 completes its rotation it will ride under the roller 77 and restore the arm 76 and aligning frame 79 to normal effective position.

Indicating mechanism.

The indicators 129 (Figs. 1 and 10) for indicating the various amounts registered

are rotatably mounted on a shaft 130 extending laterally across the top of the machine. Fast to each indicator is a pinion 131 meshing with a segment 132 loose on a rod 88. Rigid with each segment is an arm 133 (Figs. 6, 9 and 10) to which is pivoted a link 134 carrying a pin 135 engaging a slot 136 in the actuating member 106. Co-operating with the pin 135 is a lever 137 pivoted on the shaft 31 and bifurcated at its lower end to engage a roller 138 on an extension 139 of the element 107. The arrangement is such that when the members 106 and 107 are moved forward the upper end of the lever 137 will be swung rearward, the upper end of the lever and the rear end of the slot 136 co-operating to move the pin 135 and indicator setting link 134 directly from the position in which they were left by the last operation to a new position. At the end of the forward movement of the members 106 and 107 both the rear end of the slot 136 and the upper end of the lever 137 will be in engagement with the pin 135 so that the extent of the rotation of the indicator will be positively limited.

The indicators are normally held adjusted by locking arms 140 (Fig. 10) attached to the shaft 88 and engaging the teeth of an aligning element 141 rigid with each of the indicators. The shaft 88 is rocked to engage and disengage the aligning arms 140 by a cam groove 142 (Fig. 11) in the disc 58. Co-operating with this cam groove is a roller 143 on a pitman 84 pivoted at its upper end to an arm 87 attached to the shaft 88. The cam groove 142 is so shaped that the indicator locking arms 140 will be moved and held out of engagement until the elements 106 and 107 have all completed their forward movement. The locking arms are then returned to engagement so as to hold indicators in the positions to which they have just been adjusted.

45 Printer.

The ticket 91 (Fig. 8) is severed from a ticket strip 146 (Fig. 9) coming from a supply roll (not shown) preferably placed below the printing mechanism. The strip 146 passes between a feed roll 147, freely mounted upon the shaft 34, and a feed roll 148, fixedly mounted upon the shaft 46. The feed roll 148 is provided with a flange 149 at each end of the roll. During the rotation of the roll 148 and at the proper time the flange 149 will contact the strip 146; and holding it in contact with the feed roll 147, causes the strip to travel forward between an impression platen 150, and the destination device 89 and through an opening in the knife blade 100. The flange 149 on the roll 148 is of sufficient length to issue a ticket of desired size. During the time of rotation of the feed

roll 148 in which the flange 149 does not contact the upper feed roll 147, the ticket strip will remain stationary.

On the bottom side of the destination device 89 is fastened an electroplate (not shown) which prints the ticket as shown in Fig. 8. The impression platen 150 is supported by a downwardly projecting member 151 (Figs. 9 and 12) forked at its lower end so as to be guided by the shaft 35, and having a slot 152 in the upper end surrounding a rod 153. Being guided by the shaft 35 and rod 153 the platen 150 is elevated to make an impression upon the strip 146, by a cam groove 154 (Fig. 12) in the disc 60. Engaging said cam groove 154 is a cam roll 155 carried on a stud mounted in the member 151. During the rotation of the disc 60 and at the proper time the cam groove 154 will cause the impression platen 150, to make an impression from the electroplate upon the ticket strip 146.

For the purpose of making a legible impression upon the ticket to be issued, an inking ribbon is placed between the ticket strip and the electroplate. Said ribbon 156 (Figs. 1, 2, 6 and 9) is fed at right angles to the ticket strip 146 from one roller to another and over guide studs 159 projecting from the frame of the printer and when it is entirely unwound from one roller, the feeding mechanism automatically shifts to a position to rewind the ribbon on to the roller from which it was unwound. The drawings show the inking ribbon 156 about to be unwound from roller 157 and placed on roller 158.

The ribbon rollers 157 and 158 are freely mounted upon studs 162 projecting from the frame members 42 and 47, (Fig. 1) each roller carrying at its forward end a bevel pinion 163 which engages with a driving pinion 164. These driving pinions 164 are secured on the ends of a horizontal shaft 165 journaled in lugs 166 projecting from the frame members 42 and 47. This shaft 165 is given a step by step rotating motion in a clockwise direction by having securely mounted thereon a ratchet wheel 167 (Figs. 1, 2 and 9) which is moved the space of one tooth each time a ticket is issued. Engaging said ratchet 167, and for the purpose of conveying motion to the same is a pawl 168 pivoted on a stud 169 mounted on the downwardly extending arm of a bell crank 170 (Figs. 9 and 13) and held in engagement with the ratchet 167 by a spring 171. Said bell crank 170 is fast on the rod 153 and is given an oscillating motion by having a cam roller 172 engaging with a groove 173 in a disc 61 secured on the shaft 35. For the purpose of preventing a retrograde motion of the ratchet 167 (Fig. 9) a retaining pawl 174 engages with the lower side of said ratchet. Said pawl 174 is pivoted on a stud 175 mounted

in the frame member 47 and is held in contact with the ratchet 167 by a spring 176.

Referring to Figs. 1 and 2 it can be seen that the bevel pinion 164 on the left hand end of shaft 165 is in engagement with its companion bevel pinion 163, while the pinion on the right hand end of said shaft 165 is disengaged from its companion pinion 163. In this position the inking ribbon 156 will be 10 unwound from the roll 157 and rewound upon the roll 158. The engaging and disengaging of the bevel pinions is automatically effected by pins 177 fastened near the ends of the inking ribbon 156. As a pin 177 comes 15 into contact with a formed member 178 pivoted on a stud 179 mounted in the end of a lever 180, it raises said member 178 upward swinging the lever 180 on its pivot 181. The swinging motion of lever 180 is conveyed to 20 the horizontal shaft 165 by a downward projecting arm 182 carrying a pin 183 which engages with flanges 184 of a collar 185 pinned to the shaft 165. Fig. 1 shows the lever just 25 after having been swung by the pin 177 thereby disengaging the bevel pinion on the right side and engaging the pinions on the left side. After the ribbon has been almost entirely unwound from the roll 157 a pin 30 identical with pin 177 and carried near the right hand end of the ribbon will contact with the formed member 178 on the right and shift the bevel pinions into their other positions.

For the purpose of holding the bevel pinions in engagement during the rotating motion of same, there are formed in the collar 185, two annular grooves 186, in one or the other of which grooves an arm 187 engages. Said arm 187 is mounted upon the platen 35 member 151 and is raised and lowered with said platen at each operation of the machine. At the time the arm 187 is out of engagement with the collar 185 the shaft 165 is permitted to slide either to the right or to 40 the left as the case may be, under the action of the lever 180 herebefore described.

The opening in the knife blade 100 through which the ticket 91 passes in being fed from the machine, is provided with a 45 bevel cutting edge 190 (Figs. 1 and 9) on the top side of the opening which contacts with the ticket in its downward motion and with the aid of the stationary knife 191, whose upper edge is beveled, the ticket 91 50 is severed from the strip 146. The knife blade 100 is raised and lowered by an arm 192 pinned to the shaft 153 and a companion arm 193 forming an arm of the bell crank arm 193 pinned to the shaft 153. The shaft 170 also pinned to the shaft 153. The shaft 55 153 is rocked by the bell crank 170 which engages with the cam 173 hereinbefore described. The knife plate 100 is provided with openings 194 into which the rounded ends 195 of the arms 192 and 193 extend to

engage with said knife to raise and lower 65 the same. Said knife blade 100 is guided in its motion by lugs 196 at each end, the lugs being a part of the frame members 42 and 47.

70

Operation.

In order that the operation of the machine may be understood better, a resume of its operation when a local ticket is to be issued will briefly be given.

75

To operate the machine to issue a local ticket, the ticket seller inserts the proper destination device into the chute 98 (Figs. 1, 2, 6 and 9) and operates the crank 30. After completion of an operation the destination device is removed from the machine. Of course, if it is desired to print more than one ticket of the same class and for the same destination the inserted destination device is permitted to remain in the 80 machine until after the last ticket is issued.

85

The insertion of the destination device into the machine unlocks the machine for operation as its rear end engages and moves the lower end 200 of a bell crank lever 201 90 fulcrumed on the shaft 90 (Fig. 9). The rearward extending member 202 of said bell crank lever is formed near its end to hook into a notch 203 of a disc 204 which is mounted upon and pinned to the main driving shaft 31. A spring 205 will cause said bell crank lever to swing in a clockwise direction when the destination device is removed, lowering the hooked end of said lever into the notch 203 of the disc 204.

100

Each destination device is provided with a notch 207 (Fig. 14) in one of its side edges, into which a latch member 208 (Fig. 9) will fall when the destination device is inserted into the machine. This latch member 208 is pivoted upon the shaft 34 and by action of a spring 209 will normally be held in a position as shown in Fig. 9. An upward projecting arm 210 of the member 208, will engage with a notch 211 in a disc 212 secured to the shaft 31 whenever the destination device is slightly out of its proper operating position, and thereby prevent an operation of the machine.

105

Extending to the rear of the machine and being a part of said member 208, is an arm 213, the end of which is formed with an angle face 214, with which a pin 215 projecting from the side of the disc 212 engages, as the disc rotates in the clockwise direction thereby causing said arm 213 to rock in a similar direction to raise the latch 208 out of the notch 207 in the destination device, at which time the spring actuated bell crank lever 201 will move the destination device slightly forward. At the same time the hook part 202 of said bell crank lever will drop into the notch 203 in the 110

disc and prevent further operation of the machine until the destination device is again placed in proper operating position.

The destination device 89, having been properly placed in the chute 98 of the machine, the operator gives the crank 30 one complete turn in a clockwise direction. Immediately on starting the operating crank the cam 61 raises the knife blade 100 to a position which locks the destination device in position until after the actuating rack 106 and its companion plate 107 are moved forward into contact with the stop pins projecting from the top of the destination devices. After the actuating rack has come to a stop on its forward movement the totalizer is rocked into engagement with the actuating racks following which the actuating rack and its companion plate are returned to their normal position thereby entering in the totalizer an amount represented by the position of the stop pins in the destination device.

As the actuating plates are moved forward to their stopping positions, the indicators 129 are rotated by the segments 132 through the link connection 134 to the actuating plates. The forward stopping position of the actuating plates determines the position of the indicators. The indicators being placed in their new position an aligning pawl 140 which is held out of engagement with the disc 141 during the setting up of the indicators is again brought into a notch in the disc 141 by the rocking of the shaft 88 by a pitman 84 and the cam 85.

There is fastened on the under side of each destination device, a suitable electroplate for the purpose of printing data on the ticket as shown in Fig. 8. As the ticket lies between the electroplate and the impression platen, the platen is raised to print the ticket during the early part of the turning of the operating crank, by the cam 60 rotating with the shaft 35, which is geared to main operating shaft 31. After printing the ticket the platen is lowered to its normal position and the ticket is fed forward by the feed rollers 147 and 148 a distance equal to the length of the ticket, after which the knife blade 100 is lowered, severing the ticket from the strip.

While the form mechanism herein shown and described is admirably adapted to fulfill the object primarily stated, it is to be understood that it is not intended to confine the invention to the one form of embodiment herein disclosed, for it is susceptible of embodiment in various forms all coming within the scope of the claims which follow.

What is claimed is,—

1. In a machine of the class described, the combination of an insertable destination device adapted to print on a ticket, a plu-

rality of pairs of differentially and complementarily movable members, and means on said destination device for controlling the movement of said members.

2. In a machine of the class described, the combination of an insertable destination device containing a group of stops for each denominational order of an amount involved and a plurality of sets of complementary and differentially movable members, controlled by said stops.

3. In a machine of the class described, the combination of an accounting device, item entering mechanism therefor comprising a plurality of pairs of members having differential relative movements, means for actuating the members, and a destination device having differentially positioned projections arranged in pairs to represent the different digits and controlling said members to enter amounts in the accounting device.

4. In a machine of the class described, the combination of an indicating device, item entering mechanism therefor comprising a plurality of pairs of members having differential relative movements, means for actuating the members, and a destination device containing projections positioned in pairs to represent the different digits and controlling said members to display amounts by the indicating device.

5. A normally detached insertable destination device comprising a plurality of stops arranged to control differentially and complementarily movable members.

6. An amount controlling destination device comprising a plurality of laterally arranged pairs of projections corresponding in number with the number of denominations in the amount involved.

7. In a machine of the class described, a plurality of pairs of complementarily movable members, a single stop device on each member of each pair, and a single means cooperating with all of said stop devices for controlling the movements of said members.

8. In a ticket printing and issuing machine, means for registering the value of tickets issued, an insertable destination device for controlling said registering means, and means for severing said tickets and for locking said destination device in position within the machine.

9. In a machine of the class described involving ticket printing and issuing mechanism and ticket value registering mechanism, an insertable controlling device, and a ticket severing knife adapted to be moved into position upon operation of the machine, to lock said device in inserted position.

In testimony whereof I affix my signature.
THOMAS CARROLL.
